UNITED STATES PATENT OFFICE.

AARON JEDEL, OF NEW YORK, N. Y.

TRICK-BOX.

962,843.

Specification of Letters Patent. Patented June 28, 1910.

Application filed October 7, 1909. Serial No. 521,433.

To all whom it may concern:

Be it known that I, AARON JEDEL, a citizen of the United States, and a resident of the city of New York, borough of Manhattan, in the county and State of New York, have invented a new and Improved Trick-Box, of which the following is a full, clear, and exact description.

This invention relates to certain improvements in trick or joke apparatus, the object of the invention being to cover or secure articles within a box in such a manner that the retaining means will normally be invisible.

The invention involves the use of a sheet of colorless transparent glass or other similar material secured within the box and over the articles or contents of the box. When the box is handed to a person and he attempts to remove any of the articles from the box, he will, much to his surprise, find that he cannot grasp the articles because of the intervening glass. In order to render the illusion more nearly perfect, the bottom of the box preferably presents a bright light-reflecting inner surface, and this inner surface is only partially covered by the articles within the box. Thus, if the person to whom the box is handed, should instantly notice the reflection of light from the glass, he will think that this reflection comes from the reflecting inner surface of the bottom of the box. To simplify the construction and render the fastening means practically invisible, the articles themselves are preferably utilized for supporting the glass and the glass is held down in engagement with the articles by very small projections in the walls of the box.

Reference is to be had to the accompanying drawings, forming a part of this specification, in which similar characters of reference indicate corresponding parts in both the figures, and in which—

Figure 1 is a perspective view of a cigarette box constructed in accordance with my invention; and Fig. 2 is a longitudinal section through the box.

The details of construction of the box and cover are immaterial, as far as my invention is concerned. I have illustrated a cigarette box having a body portion 10 and a cover 11 hinged thereto, but it is evident that the box might be made of any different form or shape and the cover might be connected to the body of the box in any other suitable

manner instead of that shown. The metallic bottom 12 of the box is polished so as to present a bright light-reflecting inner surface, which is only partially covered by the articles within the box. In the box shown, these articles are a few cigarettes 13, although it is evident that pieces of candy or other confection, or any other suitable small articles could be used in place thereof.

Supported directly upon the articles 13, is a sheet of glass 14, cut to fit within the box and with its edges in engagement with the side walls of the box. The glass is as transparent and colorless as can be conveniently obtained and is preferably of low index of refraction. The cigarettes support the glass from beneath and the glass is held down by any suitable means. As shown, the metallic side walls of the box are punched inwardly at a few points to present projections or lugs 15 in engagement with the upper surface of the glass. The glass is thus permanently held in place and the articles are permanently retained within the box.

In using the box, it is handed to a person and accompanied by an offer of a cigarette or whatever other article the box may contain. The person receiving the box should he desire one of the articles, immediately 85 endeavors to remove it from the box and much to his surprise he finds that his fingers merely slip over the smooth upper surface of the glass without coming in contact with the articles.

Having thus described my invention, I claim as new and desire to secure by Letters Patent:

1. A trick box having a metal bottom presenting a light-reflecting inner surface, a lure within said box and only partially covering said bottom and constituting an article apparently adapted to be removed for consumption, and a sheet of colorless glass covering said lure and secured to the walls of the box, the reflection of light by the bottom of the box tending to prevent a person from noticing any reflection of light from the glass and to render the latter invisible.

2. A trick box having a metal body portion including a bottom and side walls, said bottom presenting a light-reflecting inner surface, a lure within said box and only partially covering said bottom and constituting an article apparently adapted for removal 110 from the box for consumption, a sheet of transparent colorless glass supported by said

lure and having its edges in engagement with the side walls of the box, said side walls having portions thereof bent inwardly to constitute projections or lugs for permanently retaining the glass in a position below the top of the box, and a cover for said box normally protecting said glass, said glass serving to prevent the removal of the lure from the box, and the glass being ren-

dered inconspicuous by the light's reflection 10 from the bottom of the box.

In testimony whereof I have signed my name to this specification in the presence of two subscribing witnesses.

AARON JEDEL.
